PRY BAR

Ernest O. Estwing, Rockford, Ill., assignor to Estwing Manufacturing Company, Inc., Rockford, Ill., a corporation of Illinois

Filed Jan. 21, 1965, Ser. No. 83,516

Term of patent 14 years

(Cl. D93—4)

Fig. 1.

Fig. 2.

Fig. 4.

Fig. 5.

FIGURE 1 is a perspective view of a pry bar embodying my new design;

FIGURE 2 is a plan view thereof;

FIG. 3 is a side elevational view thereof; the side opposite being substantially a mirror image thereof;

FIG. 4 is an elevational view of one end thereof;

FIG. 5 is an elevational view of the end thereof opposite the end shown in FIG. 4.

The characteristic features of my design reside in the configuration of the gad point and the merging of the upper and lower handle flanges with the gad point.

I claim:

The ornamental design for a pry bar, substantially as shown and described.
